UNITED STATES PATENT OFFICE.

HAROLD C. DWELLE, OF LEXINGTON, NORTH CAROLINA.

BOOK.

1,312,022.

Specification of Letters Patent.

Patented Aug. 5, 1919.

Application filed February 11, 1915. Serial No. 7,520.

To all whom it may concern:

Be it known that I, HAROLD C. DWELLE, a citizen of the United States, residing at Lexington, in the county of Davidson and State 5 of North Carolina, have invented a new and useful Book, of which the following is a specification.

This invention relates to books especially designed for use in keeping time in mills, 10 factories and the like, one of its objects being to provide a book the leaves of which are made up of separate slips separately removable and each of which has combined with it a duplicate and a memorandum stub, it 15 being designed to retain the duplicate for reference while the original is to be presented to the employee and contains spaces for the reception of data relative to the time employed, the amount due, the place em- 20 ployed, and other data whereby the signature of the payee constitutes both an approval of the items entered as well as a receipt for the payment of the amount represented.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed, can be made within the scope of what is claimed, without departing from the spirit of the invention.

In the accompanying drawings the preferred form of the invention has been shown.

In said drawings:—

Figure 1 is a front view of a book, the corner of the front original being lifted to expose the duplicate thereunder.

Fig. 2 is a section therethrough.

Fig. 3 is a front view of a book made up of accumulated receipts or pay checks arranged for ready reference.

Fig. 4 is a section through the structure shown in Fig. 3.

Referring to the figures by characters of reference 1 designates a slip provided, at one end, with a stub 2 divided from the main portion of the slip by a score line 3 or 50 the like whereby the slip can be readily torn from the stub when desired. Arranged back of the slip 1 is a duplicate indicated at 2' and this duplicate is so positioned that when a carbon sheet is placed between the original

and duplicate, any data entered on the original will be reproduced on the duplicate. These slips and duplicates can be assembled in any desired number to form a book.

It is to be understood that the data on each of the slips can be arranged in any manner desired to suit the conditions under which the slip is to be used. One arrangement has been illustrated in the drawings. In this form the stub is provided with the heading "Overseer's stub for charges and pay- 55 ments" and under this heading are ar- ranged horizontal lines having the respective designations "Week ending", "House No.", "Fuel \$", "Cash advanced (by form 107) \$", "Paid in full (by form 107)". That 60 end of the body or check portion 1 of the slip nearest the stub is formed with a trans- 65 verse column 4 in which are arranged the words "Please do not fold" and a set of apertures 4'. Arranged along the upper 70 margin of the check 1 is a row of spaces. The first space contains the word "Name" while the second space contains the words "Mill 75 card". The third space is blank to receive a number and the fourth space contains the 80 words "Office card" while the fifth space is blank to receive the number of the card. The six succeeding spaces are designated by 85 letters or the like to indicate the days of the week, and following these spaces are spaces containing the words "Total time", "Rate", "Amount", "Balance" and "Not over".

Under the spaces provided for the recep- 90 tion of the numbers of the mill and office cards is an elongated space 5 for the recep- 95 tion of the name of the payee and under this space 5 is another space 6 for the reception of the name of the company and the words "Time card. Pay-roll, week ending", to- 100 gether with a space for the reception of a date. Under this space 6 appears the word "Approved" and below this word are sep- 105 arate spaces 7 and 8 for the reception of the name or initials of the paymaster and over- 100 seer respectively, one of these spaces having the designation "Paymaster" while the other space has the designation "Overseer".

At one side of the space 6 is a space 9 containing the abbreviation "Dept." and let- 105 ters or the like designating different depart- 100 ments. Under those spaces containing let- 105 ters designating the days of the week are

short columns 10 and columns are also arranged under those spaces containing "Total time", "Rate", "Amount" and "Balance". Obviously two or more series of spaces can be provided for two or more weeks if desired.

Arranged under the space 5 and columns 10 is a space 12 containing the word "Occupation" and opposite this space is a series 10 of spaces 13 designated by the word "Charges" these spaces having different headings such as "Cotton", "Cloth", "Fuel" and "Rent". Under the spaces 12 and 13 is a large space 14 for the reception of the 15 signature of the payee, this space preferably containing the words "Received payment" and a line at the end of which is arranged the word "Payee". Another line is provided, designated by the word "Witness". A space 20 is provided opposite the space 14 in which appears the words "Not transferable. Report errors to overseer at once. Payment subject to the company's rules, void if altered." Arranged under the heading "not 25 over" are numerals designating dollars.

In filling out a pay check such as described, the name of the payee is placed in the space 5 and his occupation is designated in the space 12. One of the letters in the 30 space 9 is checked to indicate the department in which the payee works and the mill and office card numbers are placed in the proper spaces along the upper margin of the check. Each day of the week, the time 35 credited to the payee is entered in the proper space, the total time employed being placed in the space under the heading "Total time". The rate at which the employee is paid is entered in the proper column under 40 the heading "Rate", the total amount to be paid is entered in the column having the heading "Amount", any charges are entered in the proper spaces 13, and the balance due the payee is entered in the column having 45 the heading "Balance". Any necessary data for the protection of the overseer is entered on the stub of the check and the period for which the money is to be paid is entered in the space 6. The overseer and paymaster 50 approve the check by proper endorsement within the spaces 8 and 7 and one of the numerals under the heading "Not over" is punched. This check is then torn from its stub, it being understood that the data entered therein will be reproduced on the 55 duplicate. The check when removed is handed to the payee who places his signature in the space 14 provided the data entered on the check is correct. When the payee presents 60 the check to the office he will be paid the value expressed thereon.

The checks thus collected at the office are kept together for ready reference preferably as shown in Figs. 3 and 4. They are arranged 65 to form pages of a loose leaf book,

the checks of each page being assembled in lapped relation, as shown particularly in Fig. 3, the uppermost check being lapped by the next adjoining check and this arrangement being followed from the top to 70 the bottom of the page. Thus it will be seen that when the uppermost check is turned from right to left of the book, all of the checks forming the page will be likewise carried from right to left. However, the 75 lowermost check can be turned from right to left without effecting the other checks forming the page. This arrangement permits of ready access to any one of the checks and also enables the pages to be quickly 80 turned.

Importance is attached to the fact that a check such as herein described can be quickly checked or marked to indicate the department in which it is used, and contains 85 an itemized statement as to financial relations of the payee with the employer which statement is approved by the payee when placing his signature to the check and which check is preserved as a receipt. The stub is 90 retained temporarily by the overseer for his own protection and contains any necessary data, while the duplicate made while filling out the original of the check may be 95 preserved by the overseer as a permanent record.

While in Fig. 1 each page of the book is shown made up of a single stub and check, it is to be understood that if preferred, each page can be made up of a plurality of stubs and checks arranged one above the other and 100 separated by score lines. This construction is so obvious that it is not deemed necessary to illustrate it in detail.

What is claimed is:—

A book including separate pages or 105 groups of similar original checks, all of the checks of each page or group being of the same width and length and all of the pages or groups being bound together along one edge and being superposed one upon the 110 other, each check of each of said pages or groups having a longitudinal row of spaces parallel with and adjacent the upper edge thereof, said spaces being suitably designated and being adapted to receive the name 115 of the payee, data indicating actual time put in, rate of payment, total amount earned, and balance due, the said spaces on all of the checks of each group being constantly exposed to view, there being additional spaces upon each check and below 120 said constantly exposed row, for the reception of detailed information relative to the data in said exposed row of spaces and for the reception of the signature of the payee, 125 the checks of each group being arranged in lapped relation and at different distances from opposed ends of the group thereby to form a page and each check, in each group, when turned, being adapted to turn all the 130

remaining checks located beyond one edge thereof, all of the checks having their corresponding ends flush and being secured together at one of said ends, thelapping upper 5 and lower edges of the checks being at right angles to the line on which the checks are bent when turned.

In testimony that I claim the foregoing as my own, I have hereto affixed my signature in the presence of two witnesses.

HAROLD C. DWELLE.
